UNITED STATES PATENT OFFICE.

MILTON L. GILLESPIE, OF LOS ANGELES, CALIFORNIA.

FOLDING-TABLE CONSTRUCTION.

Application filed July 25, 1927. Serial No. 208,071.

This invention pertains more specifically to a hinge construction for the folding leaves of an extension table.

A chief object of this invention is to provide an extension leaf hinge construction for tables provided with depending aprons around the table top edges which will not materially alter or mutilate the aprons when the leaves are secured thereto.

10 Another object is to provide a hinge construction that may be readily stamped from sheet metal, that is easy of attachment to the leaves and table apron, and that consists of only a single member.

15 In extension leaf tables that may be converted from one type, such as a library table, into a table of another type as a dining table, the leaf hinges have been of a special type in order to avoid the table apron when 20 the leaf is swung to an extended position, such hinges generally having one of the leaves of curved formation adapted to pass below the table apron when drawn to an extended position. With such form of 25 hinges there is no necessity of mutilating the table aprons in any manner, but in inexpensive table constructions such hinges add greatly to the expense of construction and are for that reason objectionable. By means 30 of my inexpensive die formed metal hinge the only mutilation of the table apron necessitated is a narrow vertical slot in the apron which is practically unnoticeable.

The above and other objects are accomplished by means of the hinge construction described in the following specification, reference being had to the accompanying drawings forming a part thereof, in which;

35 Fig. 1 is a side view of a table with the extension leaves folded beneath the top.

Fig. 2 is a bottom plan view of the table top showing the leaves in an extended position.

40 Fig. 3 is an enlarged transverse section 45 through the table top taken on line 3—3 of Fig. 1.

Fig. 4 is a similar view showing the leaves folded beneath the top.

Fig. 5 is an enlarged detail edge view of 50 the table top showing the manner of attaching the hinges to one of the table aprons.

Fig. 6 is a perspective view of the leaf hinge.

In an embodiment of the present invention, 55 5 designates a table of the "library" type, consisting of end supporting legs 6

secured together at their lower ends by a cross brace 7, and a table top 8 at their upper ends. Secured around the edges of the top 8 are side depending aprons 9 and 10 and end 60 aprons 11.

The hinges 12 for attaching the foldable leaves 13 and 14 to the table are preferably formed of sheet metal die formed and consisting of a flat arm 15 having a hole 16 at 65 one end and a leaf attaching portion 17 at the opposite end bent at right angles to the arm portion. Two hinges are required for each foldable leaf in a table of normal dimensions, and are affixed to the leaves and 70 aprons adjacent the table ends, the leaf attaching portion 17 of the hinge being secured to the innerface of the leaf at its table top meeting edge, while the arm 15 is swingingly secured by a pivot pin 18 to the end 75 of apron section 20. The end sections 21 of the apron 9 abut against the arms 15 of the hinges, thus forming narrow vertical slots 22 in the apron which will scarcely be visible in an assembled table.

80 Each leaf is supported when in an extended position by the usual slides 23, 24 disposed in a guide-way 25 formed on the undersurface of the table top, and secured to this guide-way midway of its ends are spring 85 leaf catches 26 for holding the leaves in their chambered positions. It will be understood that other forms of leaf holders may be substituted for one shown if desired.

85 In attaching the extension leaves to the 90 table top, the apron sections 20 are first secured to the top, the hinges with the leaves secured thereto are then pivoted to the ends of the said sections, after which the end sections 21 of the aprons are secured in position.

95 From the above description it will be apparent that I have produced a simple form of hinge for extension table leaves, and as the table apron is slotted to permit of a 100 movement of the hinges when the leaves are swung to an extended or chambered position the hinges need only be formed of a single leaf member. Further, as noted heretofore, as the apron slots are very narrow the same 105 will not disfigure the aprons, nor will the slots present an unsightly appearance.

What I claim is:

1. An extension leaf table construction comprising a table top provided around its 110 edges with depending aprons, one of the side aprons being vertically slotted for the re-

ception of hinges, a single leaf hinge mounted in each of the slots of said apron and pivoted thereto to swing from an extended to a closed position, and an extension leaf 5 rigidly secured to the free end of each of said hinge leaves.

2. An extension table embodying a stationary table top, a depending apron around the edge of the table top, a leaf movable with 10 relation to the table top and having an edge

adapted to register with the table top edge, the apron being provided with vertical hinge slots, and single leaf hinges, one end of said hinges engaging the apron slots and pivoted to one wall of the slot, and their free ends 15 rigidly secured to the underface of the movable leaf.

In testimony whereof I affix my signature.

MILTON L. GILLESPIE.
